UNITED STATES PATENT OFFICE.

ALAN R. FERGUSSON, OF BUFFALO, NEW YORK.

TOY SWITCH.

Application filed March 19, 1923. Serial No. 625,990.

To all whom it may concern:

Be it known that I, ALAN R. FERGUSSON, a citizen of the United States, residing at Buffalo, in the county of Erie and State of New York, have invented certain new and useful Improvements in Toy Switches, of which the following is a specification.

This invention relates to switches for toy or miniature railways, an object of the invention being to provide a strong and durable construction which will withstand long and continued hard usage and will not get out of order.

A further object of this invention is to provide an improved switch mechanism, which by reducing the cost of manufacture and the cost of material may be manufactured at a minimum of expense, and yet will combine with such cheapness, a high degree of commercial attractiveness.

A further object of this invention is to provide a reversible or combined right and left handed switch which may be used interchangeably at any point in the railway system.

A further object of this invention is to provide a toy switch which will be greatly simplified in construction, eliminating for instance, the necessity of using frogs, intersecting rails and operating levers, and yet so constructed that the operation of switching can be accomplished by the child with great ease and rapidity.

A further object of this invention is to provide an improved toy railway switch having relatively shiftable switching members adapted to be guided one relatively to the other, and which is adapted to be connected to one or more wire track sections.

A further object of this invention is to provide a toy railway switch construction having means for permitting the same to be connected interchangeably to one or more wire track sections, or if desired to the conventional track section on the market, or to both.

Other objects of this invention will appear in the following description thereof and the appended claims, reference being had to the accompanying drawings forming a part of this specification, wherein like reference characters indicate corresponding parts in the several views, and wherein Fig. 1 is a plan view illustrating a form of my invention; Fig. 2 is a cross section taken substantially on line 2—2 of Fig. 1; Fig. 3

is a bottom plan view partly broken away of the switch shown in Fig. 1; Fig. 4 is a detail perspective view illustrating a manner in which one of the switch members 60 may be connected to a track section; Fig. 5 is a plan view illustrating a somewhat modified form of my invention; Fig. 6 is a perspective view of one of the switch members thereof; Fig. 7 is a perspective view of 65 the other switch member thereof; Fig. 8 is a plan view illustrating a somewhat modified form of construction; Fig. 9 is a bottom plan view of the switch members; Fig. 10 is a detail perspective view of the pivot 70 plate for the swinging track section, and Fig. 11 is a cross section taken substantially on line 11—11 of Fig. 8.

Before explaining in detail the present improvement and mode of operation thereof, I desire to have it understood that the invention is not limited to the details of construction and arrangement of parts which are illustrated in the accompanying drawings, since the invention is capable of 80 other embodiments, and that the phraseology which I employ is for the purpose of description and not of limitation.

Heretofore in switches which have been conventionally used on the market it has 85 been necessary to make both right and left handed switches, the left handed switch being complementary to a right handed switch. For instance, if it were desired to switch the train from the main line to a 90 line extending off to the right of the main line, a right handed switch was necessary, and in order to return the train to the main line again it was necessary to use a left handed switch. Thus, heretofore, it was 95 necessary to construct two different kinds of switches, namely the right handed switch and the left handed switch, and in purchasing switches in the stores it was necessary for the salesman to carefully instruct customers as to the necessity of buying complementary right and left handed switches.

Therefore, not only has the cost of manufacture been increased due to the fact that two different types of switches had to be 105 provided, but also due to the tendency of making mistakes in buying two right or left handed switches instead of one of each kind, considerable sales resistance inevitably resulted. The present invention eliminates 110 these disadvantages, and combines in a single construction both a right handed and a

left handed switch, or in other words the present invention provides a reversible switch which may be interchangeably used at any point on the railway system as either a right handed or a left handed switch.

In general, the present improved construction comprises a pair of relatively shiftable switching members having cooperating means for guiding one relatively to the other, one of the switching members having connection with two pairs of rails, one pair located at one side of the other pair, and the other switching member having connection to a pair of rails, so that one of the switching members may be shifted relatively to the other to bring different pairs of rails of the two members into alinement. Thus, one of the switching members may be shifted into reverse positions with relation to the other switching member for forming either a right or left handed switch.

Referring particularly to Figs. 1 to 4 inclusive of the drawings, wherein I have illustrated one form of my invention, it will be seen that this switch construction comprises a preferably stationary switching member 9, which in the present instance, comprises a plate preferably stamped out of sheet metal having bent up side edges 10 and 11. The plate 9 is also provided with projecting portions 12 and 13 at one side thereof, these portions being stamped up with shoulders 14 and 15 so as to cause the parts 12 and 13 to lie above the plane of the plate 9 and substantially in the plane of the switch plate 28, hereinafter described. The lateral edges of the projecting portion 12 are preferably coiled to form tubular, cylindrical, rail-forming ribs 16, and the projecting portion 13 is in like manner coiled at the edges thereof to form similar coiled rail-forming ribs 17.

In the present instance, the rail ribs 16 are detachably connected to a wire track section. By means of dowels. A dowel 18 is inserted into a coiled rail rib 16 and is adapted to releasably extend into a bore 23 or any suitable tubular portion at the end of a wire rail 22. The other wire rail 20 of this track section is preferably detachably connected to the opposite rail rib 16 by means of a dowel 21 adapted to releasably extend thereinto. The coiled rail-forming ribs 17 are also preferably connected to wire rails 24 and 26 in the same manner, that is by means of a dowel 19, secured within the coiled opening of one of the rail ribs and releasably extending into a bore or other tubular portion 27 at the end of the wire rail 26, the wire rail 24 being provided with a dowel end 25 releasably extending into the coiled opening of the other rail rib 17.

The switching member 9 forms in the present instance a guide for a transversely shiftable switching member 28. This latter

member preferably comprises a plate stamped out of sheet metal and having the side edges thereof partially coiled at 29 and 30 to provide guide portions of suitable shape to receive the cylindrical ends of wire rails 31 and 32. In the construction shown in Fig. 1 the rails 31 and 32 are rigidly secured to the plate 28 as by spot-welding, but in Fig. 4 these rails are illustrated as detachably connected to the shift plate 28 by means of lugs 31^a adapted to releasably extend into openings 32^a. In this manner the releasable connections between the wire rails 31 and 32 and the plate 28 form a spring or tension joint, since the free spring ends of the wire rails are contracted or tensioned sufficiently to permit the lugs 31^a to spring into the openings 32^a. The wire rails 31 and 32 in the present instance are supported by means of wire ties 33 and are preferably spot-welded thereto, the construction thus providing a strong and durable switching mechanism.

The shift plate or switching member 28 is guided over the switching member 9, and the members are held in proper position by means of suitable interlocking guide connections. As illustrated particularly in Fig. 3, the plate 28 has a projecting portion 34 bent over and under an edge of guide plate 9 so as to freely embrace the same. Also, the plate 9 is provided with a guide slot 35 and a guide lug 36 is stamped out of plate 29 so as to extend into the slot 35 and freely embrace an edge thereof as shown in Fig. 3.

It will be seen that the guide slot 35 is of sufficient length so that the ends 37 and 38 thereof will form stops for the lug 36. The shiftable switch plate 28 is also provided with an integral projecting handle member 39 and it will be seen that by grasping this handle the shift plate 28 may be shifted in reverse directions so as to bring the rails 31 and 32 into alinement with either the pair of companion rails 17, or the pair of companion rails 16, thereby causing rails 31 and 32 to be brought into alinement with either of the pair of rails 24 and 26, or rails 20 and 22. The exact alinement of the several pairs of rails is obtained when the lug 36 reaches either end of the slot 35. The play or free lateral movement in a series of jointed or connected track sections terminating in rails 31 and 32 is sufficient to permit a lateral movement of the shiftable switch member 28, at the switching point so that a train may be readily switched from one line of track to the other.

The wire rails 31 and 32 may be releasably joined or connected end to end to an adjacent track section by a dowel construction. As shown in Fig. 1 the wire rail 31 terminates in a reduced dowel-forming end 40 which is insertible in a tubular end 41, of a wire rail 42 of the adjacent track section.

The wire rail 32 is preferably provided with a bore at its end or a tubular portion 44 into which may be releasably inserted a dowel end 43 of wire rail 45. This dowel 5 construction not only permits the wire rails 31 and 32 of the switch to be connected to an adjacent wire track section, but also permits the same to be connected if desired to a conventional track section on the market.

10 In the construction illustrated in Figs. 5 to 7 inclusive, the guide member 46 is of substantially the same form as hereinbefore described, the guide member being provided with end guides 47 and 48 and having projecting rail-forming portions 49 and 50 which are stamped up above the plane of the plate 46, the shoulders 51 and 52 thus permitting the parts 49 and 50 to extend in the same plane as the shift plate 65. The 20 projecting portion 49 is coiled up at its edges to form cylindrical, tubular, rail ribs 53, and the part 50 is in like manner formed with rails ribs 54. Dowels 55 and 56 are secured within the coiled rails 53 and 54 respectively. The wire rail 57 of an adjacent section is provided with a reduced dowel forming end 58 releasably insertible within one of the coiled rail portions 53, the other wire rail 59 of this section having a bore 30 or tubular end 57 adapted to receive the dowel 55. In like manner the wire rail 61 of an adjacent section has a dowel 62 extending into a coiled rib 54, and the dowel 56 is adapted to be inserted into a bore or tubular end 64 of the other wire rail 63 of this section.

Guided upon the plate 46 is a switch member 65 having the edges 66 and 67 thereof coiled to form spaced ribs, one of these coiled 40 rail portions 67 has a dowel 68 secured in one end thereof, and the shiftable switch member 65 is also provided with a projecting handle member 69. The plate 46 is provided with a lengthwise extending guide 45 slot 72, and the shift plate 65 is interlocked with plate 46 by means of a bent portion 70 embracing an edge of plate 46 and also by means of a bent lug 71 extending into and embracing an edge of the guide slot 72.

50 A track section is adapted to be detachably connected to the switch member 65, and in the present instance, a wire track section is detachably connected thereto. This section comprises wire rails 73 and 74 secured 55 as by means of spot-welding to wire cross ties 75. The wire rail 73 is also provided with a reduced dowel end 77 insertible in the coiled opening of the rail 66, and the wire rail 74 is provided with a bore or other 60 tubular end portion 76 adapted to receive the dowel 68. From this construction it will be readily seen that when the rails 73 and 74 are connected to the rails 66 and 67 of the switch member 65, these rails may be switched into 65 alinement with either pair of companion

rails 61 and 63, or 57 and 59, merely by grasping the handle member 69 and shifting the switch member 65 over the guide member 46. The several rails 66, 67, 73, and 74 will be guided into exact alinement with 70 the several pairs of rails 54, 61, 63, 53, 57, and 59, by virtue of the fact that the guide lug 71 traveling in the slot 72 will be limited in its movement by the ends of the guide slot 72.

75 In Figs. 8 to 11 inclusive, a somewhat modified form of my invention is illustrated. In this instance, the guide plate or switch member 78 comprises a curved plate having the ends thereof bent up at 79 and 80 to form 80 guide portions. The construction of this guide plate is substantially similar to that hereinbefore described with the exception that the projecting portions 81 and 82 extend in diverging relation, the extension 81 having the edges thereof coiled to form rail members 83 and 84, and the extension 82 also having the edges thereof coiled to form rail members 85 and 86. A dowel 88 is secured within the 85 coiled rail member 84 and the coiled end 87 of rail 83 is adapted to releasably receive a suitable dowel on the end of a wire rail of an adjacent section, the construction thereof being the same as hereinbefore 90 described. In like manner the coiled rail member 86 is provided with a dowel 90 and a dowel on the end of a wire rail of an adjacent section is adapted to releasably extend into the coiled end 89 of rail member 10055 10060 10065 10070 10075 10080 10085 10090 10095 10100 10105 10110 10115 10120 10125 10130 10135 10140 10145 10150 10155 10160 10165 10170 10175 10180 10185 1019

the wire rails 96 are bent or turned downwardly, substantially at right angles and these ends 96^b project through the slots 99 and are suitably held therein as by means of washers 100 secured to the ends of the bent portions 96^a.

It will be seen that the inner ends 101^a of the rail portions 101 are cut away to form tapered or pointed ends, and these points 101^a overlie the outer ends of the slots 99. Thus, when one of the wire rails 96 has its bent end 96^b impinging against the outer end of a slot 99 as shown in Fig. 8, the point 101^a will overlap the wire rail, thus 15 forming a continuous joint between wire rail 96 and rail 101. When however, the bent portion 96^b of a wire rail 96 impinges against the inner end of a slot 99 the point 101^a will still form substantially a continuous joint between the wire rail 96 and the 20 coiled rail 101. A dowel 102 may be secured within one of the coiled rails 101 and it will be understood that the rails 101 may be therefore readily connected to an adjacent 25 track section in the usual manner.

It will be readily understood from this construction that the switching operation is accomplished by grasping the handle 95 and shifting the switch member 91 over the 30 switch member 78, the interlocking parts of the two switch members causing the switch member 91 to be guided in the proper path. In this operation the rails 96 will be 35 swung or rotated about their pivots on the pivot plate 98, the slots 99 being preferably provided so as to give the proper play to the pivots. The rail portions 101 of course, are connected to the usual jointed track sections forming the main line and the plate 40 98 is preferably positioned so that the rails 101 will extend in a direction passing through the median line of the curved guide plate 78. Thus, in the operation of switching the train from one pair of rails 83, 84, 45 to the other pair of rails 85, 86, the wire rails 96 will be swung in an arc corresponding to the curvature of the guide plate 78.

It is to be understood that by describing in detail herein any particular form, structure, or arrangement, it is not intended to 50 limit the invention beyond the terms of the several claims or the requirements of the prior art.

Having thus explained the nature of my 55 said invention and described a way of constructing and using the same, although without attempting to set forth all of the forms in which it may be made, or all of the modes of its use, I claim:

60 1. Switch mechanism for toy or miniature railways comprising mechanism for connecting a track section with either of a pair of independent track sections, said mechanism including means detachably 65 connected to a section and shiftable into

different positions for forming either a right or left handed switch.

2. A reversible right and left handed switch mechanism comprising two pairs of companion rails, one pair of companion rails located entirely at one side of the other pair, and a pair of rails shiftable into alignment with either pair of rails. 70

3. A reversible right and left handed switch comprising switch means having two pairs of companion rails, one pair of companion rails located entirely at one side of the other pair, and switch means adapted to be connected to a pair of companion rails, one of said switch means being shiftable relatively to the other to bring a pair of rails of one switch means into alignment with a pair of rails of the other switch means. 75

4. In a toy railway switch the combination of two sets of rails, one set comprising two pairs of companion rails, one pair located entirely at one side of the other pair, and the other set comprising a single pair of rails, one of said sets being shiftable relatively to the other set to bring different pairs of rails into alignment. 80

5. A reversible right and left handed switch comprising switch means having two pairs of companion rails, one pair of companion rails located at one side of the other pair, and switch means adapted to be connected to a pair of rails, one of said switch means being shiftable relatively to the other to bring a pair of rails of one switch means into alignment with a pair of rails of the other switch means, one of said switch means having guide means cooperating with the other. 90

6. In a toy railway switch the combination of two pairs of companion rails, one pair of companion rails located at one side of the other pair and each pair adapted to be connected to a track section, and a pair of wire rails shiftable into alignment with either 100 pair of companion rails. 105

7. In a toy railway switch the combination of two pairs of companion rails, one pair of companion rails located at one side of the other pair and each pair adapted to 115 be connected to a track section, a pair of wire rails, and shiftable means connected to said wire rails for shifting the same into alignment with either pair of companion rails. 120

8. In a toy railway switch the combination of guide means, a pair of rail portions connected thereto and adapted to be connected to a track section, a second pair of rail portions connected thereto at one side 125 of said first rail portions and adapted to be connected to a track section, and means for shifting a pair of rails into alignment with either of said pairs of rail portions.

9. In a toy railway switch the combina- 130

tion of guide means, a pair of rail portions connected thereto and adapted to be connected to a track section, a second pair of rail portions connected thereto at one side of said first rail portions and adapted to be connected to a track section, a pair of connected rails, and shiftable means connected to the ends of said rails and shiftable over said guide means for positioning said connected rails in alinement with either of said first pairs of rail portions.

10. In a toy railway switch the combination of guide means, a pair of rail portions connected thereto and adapted to be connected to a track section, a second pair of rail portions connected thereto at one side of said first rail portions and adapted to be connected to a track section, a pair of connected rails, and shiftable means connected 15 to the ends of said rails and shiftable over said guide means for positioning said connected rails in alinement with either of said first pairs of rail portions, said guide means and shiftable means having cooperating 20 guide portions.

11. In a toy railway switch the combination of guide means, a pair of rail portions connected thereto and adapted to be connected to a track section, a second pair of rail 25 portions connected thereto at one side of said first rail portions and adapted to be connected to a track section, a pair of connected rails, and shiftable means connected to the ends of said rails and shiftable over 30 said guide means for positioning said connected rails in alinement with either of said first pairs of rail portions, said guide means and shiftable means having one a slot and the other means adapted to be guided in 35 said slot.

12. In a toy railway switch the combination of a switch member bent to form a pair of rail portions, and a pair of rails located in alinement with said rail portions.

45 13. In a toy railway switch the combination of a pair of relatively shiftable switching members having cooperating guide means, one of said members being bent to form a pair of rail portions, and the other member having means for positioning a pair 50 of rails in alinement with said rail portions.

14. In a toy railway switch the combination of a switching member having two pairs of companion rail portions formed therefrom, and a switching member having a pair 55 of rail portions connected thereto, one of said members shiftable relatively to the other to bring rail portions of one member into alinement with rail portions of the other 60 member.

15. In a toy railway switch the combination of a switching member bent to form a pair of rail portions, and a pair of rails located in alinement with said rail portions, said rail portions having means for connect-

ing the same to an independent rail section.

16. In a toy railway switch the combination of a pair of switch members guided one relatively to the other, one of said members having two pairs of rail portions and the other member having a single pair of rail portions, certain of said rail portions being formed from a member, and said members being shiftable one relatively to the other to bring a pair of rail portions of one member 70 into alinement with a pair of rail portions of the other member.

17. In a toy railway switch the combination of a pair of switch members guided one relatively to the other, one of said members 80 having two pairs of rail portions and the other member having a single pair of rail portions, certain of said rail portions being formed from a member, and said members being shiftable one relatively to the other 85 to bring a pair of rail portions of one member into alinement with a pair of rail portions of the other member, said members having cooperating guide portions.

18. In a toy railway switch the combination of a pair of switch members, one of said members having two pair of rail portions and the other member having a single pair of rail portions, certain of said rail portions being formed from a member, and 90 said members being shiftable one relatively to the other to bring a pair of rail portions of one member into alinement with a pair of rail portions of the other member, said members having one a slot and the other a 95 member guided in said slot.

19. In a toy railway switch the combination of a pair of switch members, one of said members having two pairs of rail portions and the other member having a single 100 pair of rail portions, certain of said rail portions being formed from a member, and said members being shiftable one relatively to the other to bring a pair of rail portions of one member into alinement with a pair of rail portions of the other member, said members having one a slot and the other a 105 member guided in said slot.

20. In a toy railway switch the combination of a pair of relatively shiftable sheet metal switch members guided one relatively to the other, rails connected to one member, and rails bent up from the other member. 110

21. In a toy railway switch the combination of a guide member having rails connected thereto, and a shiftable switching member carried by said guide member and 115 bent to form a pair of spaced rail portions.

22. In a toy railway switch the combination of a guide member having rails connected thereto, a shiftable switching member carried by said guide member and hav- 120 125 130

- ing spaced rail portions, and means for detachably connecting a rail section to said switching member.
23. In a toy railway switch the combination of a guide member, a shiftable switching member having a guiding connection with said member, and a handle member formed from one of said members.
24. In a toy railway switch the combination of a guide member, a shiftable switching member carried thereby, a handle member connected to one of said members, means for detachably connecting a rail section to one of said members at one side of the guide member, and means for detachably connecting a pair of rail sections to the other member at the opposite side of the guide member.
25. In a toy railway switch the combination of a pair of switch members shiftably guided one relatively to the other, means for detachably connecting a rail section to one of said members, and means for detachably connecting a pair of rail sections to the other member.
26. In a toy railway switch the combination of a guide member, a movable switching member carried thereby, means for detachably connecting a rail section to said switching member, and means for detachably connecting a pair of rail sections to said guide member, said guide member and switching member having cooperating means for guiding one relatively to the other.
27. In a toy railway switch the combination of a pair of relatively shiftable switching members, means for detachably connecting a pair of rail sections to one of said members and means for connecting a rail section to the other member.
28. In a toy railway switch the combination of a pair of relatively shiftable switching members, means for detachably connecting a pair of wire rail sections to one of said members and means for connecting a wire rail section to the other member, said switching members having cooperating means for guiding one relatively to the other in a predetermined path.
29. In a toy railway switch the combination of a pair of relatively shiftably switching members having means for guiding one relatively to the other in a predetermined path, a pair of wire rails detachably connected to one of said switching members, and two pairs of wire rails detachably connected to the other member.
30. In a toy railway switch, a switching member having parts thereof coiled to form rail members and adapted to receive a dowel member.
31. In a toy railway switch, the combination of a pair of relatively shiftable switching members and a rail section connected to one of said members, said rail section including a wire rail terminating in a dowel-forming portion.
32. In a toy railway switch, the combination of a pair of relatively shiftable switching members, one of said members having a pair of bent-up ribs forming rails, and a pair of spaced wire rails connected to the other member, one of said wire rails terminating in a dowel-forming portion.
33. In a toy railway switch, the combination of a pair of relatively shiftable switching members, one of said members having a pair of bent-up ribs forming rails, and a pair of spaced wire rails connected to the other member, one of said wire rails terminating in a tubular portion for receiving a dowel end of an adjacent rail section.
34. In a toy railway switch the combination of a pair of relatively shiftable switching members, two pairs of companion wire rails located at one side of said members and one of said pairs located at one side of the other pair, a pair of wire rails located at the opposite side of said members, and means for detachably connecting a pair of said rails to a switching member.
35. In a toy railway switch the combination of two pairs of companion wire formed rails, one pair of companion rails located at one side of the other pair and each pair adapted to be connected to a track section, and a pair of rails shiftable into alignment with either pair of companion rails.
36. A reversible right and left handed switch mechanism comprising two pairs of companion wire formed rails, one pair of companion rails located entirely at one side of the other pair, and a pair of wire formed rails shiftable into alignment with either pair of rails.
37. In a toy railway switch the combination of two sets of rails including wire formed rails, one set comprising two pairs of companion rails, one pair thereof located entirely at one side of the other pair, and the other set comprising a single pair of rails, one of said sets being shiftable relatively to the other set to bring different pairs of rails into alignment.
38. In a toy railway switch mechanism the combination of two sets of rails, one set comprising two pairs of companion rails, one pair of companion rails being located entirely at one side of the other pair, and the other set comprising a pair of rails, one of said sets being shiftable relatively to the other set to bring different pairs of rails into alignment, and wire formed supporting means for one of said pairs of rails.
39. In a toy railway switch the combination of a pair of relatively shiftable switching members having cooperating means for guiding one relatively to the other, two pairs of companion rails connected to one of the

said members, one pair of companion rails being located at one side of the other pair, and a pair of rails having a detachable spring connection with said other switching member.

40. In a toy railway switch the combination of a pair of relatively shiftable switching members having cooperating means for guiding one relatively to the other, two pairs of companion rails connected to one of the

said members, one pair of companion rails being located at one side of the other pair, a rail section comprising wire ties and a pair of wire rails connected to said ties, said wire rails having a detachable spring connection with said other switching member. 15

Signed at Buffalo, Erie county, New York, this 16 day of March, 1923.

ALAN R. FERGUSSON.
